(57) **CLAIM**

The ornamental design for a plate carrier vest, as shown and described.

DESCRIPTION

FIG. 1 is a top plan view of a plate carrier vest, showing our new design.

FIG. 2 is a bottom plan view of the plate carrier vest of FIG. 1.

FIG. 3 is a front elevation view of the plate carrier vest of FIG. 1.

FIG. 4 is a back elevation view of the plate carrier vest of FIG. 1.

FIG. 5 is a right side elevation view of the plate carrier vest of FIG. 1.

FIG. 6 is a left side elevation view of the plate carrier vest of FIG. 1.

FIG. 7 is a front perspective view of the plate carrier vest of FIG. 1.

FIG. 8 is a back perspective view of the plate carrier vest of FIG. 1 with side straps shown removed from the plate carrier vest; and,

FIG. 9 is an exploded view of the plate carrier vest of FIG. 1.
